UNITED STATES PATENT OFFICE

PIERRE DESGOUTTES, OF LYON, FRANCE.

VALVE-ACTUATING MECHANISM FOR INTERNAL-COMBUSTION ENGINES.

1,099,491.

Specification of Letters Patent. Patented June 9, 1914.

Application filed February 15, 1913. Serial No. 743,558.

To all whom it may concern:

Be it known that I, PIERRE DESGOUTTES, a citizen of the French Republic, residing at Lyon, in France, have invented certain new and useful Improvements in Valve-Actuating Mechanism for Internal-Combustion Engines, of which the following is a specification.

This invention relates to improvements in valve actuating mechanism for internal combustion engines.

The use of a cylindrical valve member concentric with the cylinder and having a movement the trajectory of which is practically circular or elliptic, is known in valve mechanism for internal combustion engines. The said movement which is obtained by the combination of a longitudinal reciprocating movement with a simultaneous partial reciprocating rotary movement has hitherto only been effected by means of complicated mechanical devices.

The present invention has for its object a simple mechanism by means of which the cylindrical valve member is given the necessary movement.

An example of construction of the mechanism for operating the distribution valve for a four stroke cycle motor is illustrated in the annexed drawings, in which—

Figure 1 is a vertical section of the motor. Fig. 2 is a diagram illustrating the movement of the valve. Fig. 3 is a section on line A—A of Fig. 1 showing in plan and on a larger scale the actuating mechanism of the valve.

The valve 1 arranged between the cylinder and the piston is of a known type and of which as shown in Fig. 2 the orifices 2 and 3 successively uncover ports 4 and 5 made in the cylinder wall and respectively serving for the intake and the exhaust. The valve 1 moves over an elliptical trajectory 6 generated in the following manner: A shaft 7 preferably arranged parallel to the motor shaft 8 rotates at a relative speed which depends on the type of motor; in the example shown the said shaft 7 rotates at half the speed of the shaft 8. The shaft 7 is provided opposite each cylinder with a crank 9 the diameter a of the throw of which is equal to the vertical stroke of the valve 1.

On the crank 9 is mounted a perforated block 10 carried by a vertical trunnion 11 which pivots in a sleeve 12 connected to the lower part of valve 1 by an arm 13 arranged at a mean angle of about 45° with regard to the axis of the crank 9. The valve is thus united with the crank 9, and its movement must consequently coincide with the vertical movement of the crank but by reason of the obliqueness of the arm 13 with respect to the crank 9, the trunnion 11, the distance of which from the center of the valve is constant, is forced to execute an angular displacement of an amplitude b as shown in Fig. 3 which corresponds to a linear displacement c on the outer surface of valve 1. The latter is thus simultaneously submitted to two movements; the first vertical of an amplitude a , the second lateral of an amplitude c . The combination of these two movements gives a resultant trajectory, practically taking the form of an ellipse having as axes the distances a and c . The construction of this device only requires that the trunnion of the crank 9 has sufficient length to allow the block 10 to move over the distance d which corresponds to the angular distance mentioned. This arrangement allows of easily determining the movement of the valve for each of the cylinders and the parts are simple and easily manufactured. When the motor has a plurality of cylinders, the shaft 7 is provided with as many cranks 9 as there are cylinders these cranks being arranged at angles suitable for the various cylinders.

It is well understood that the described method of actuating the valve is applicable to all kinds of two or four stroke-cycle motors, the frequency at which the distribution ports should be uncovered by the valve, being taken into account which is easily obtained by varying the relation of the respective speeds of the motor shaft and of the shaft which actuates the valve.

What I claim as my invention and desire to secure by Letters Patent of the United States is:—

100
Valve actuating mechanism for internal combustion engines comprising in combination a cylindrical valve member, an arm rigidly fixed thereto, a shaft adapted to be

rotated by the engine, a crank on said shaft, a perforated block mounted on said crank and movable thereon, a trunnion connected to said block, and a sleeve fixed to said arm and mounted on said trunnion the said arm being arranged obliquely to said crank and to the plane of rotation thereof.

In witness whereof I have signed this specification in the presence of two witnesses.

PIERRE DESGOUTTES.
